UNITED STATES PATENT OFFICE.

TOM L. JOHNSON, OF CLEVELAND, OHIO.

TURN-TABLE.

SPECIFICATION forming part of Letters Patent No. 427,328, dated May 6, 1890.

Application filed March 8, 1888. Serial No. 266,539. (No model.)

To all whom it may concern:

Be it known that I, TOM L. JOHNSON, of Cleveland, in the county of Cuyahoga and State of Ohio, have invented a new and useful Improvement in Turn-Tables, which invention is fully set forth and illustrated in the following specification and accompanying drawings.

This invention relates to turn-tables especially adapted for use in streets for turning street-cars, which turn-tables may be used either without rails or with rails, cast or otherwise attached to the top of the table, in which latter case a catch is used to stop the revolution of the table at the exact point to make connection with the track-rails.

The objects and advantages of the invention are as follows:

First. To improve the form of the catch where rails are used. Where no rails are used of course no catch is necessary.

Second. In turn-tables of this description, where it is necessary to maintain the surface of the table level with the surrounding road-bed, notwithstanding the wear of the balls on which the table revolves and the settling of the whole foundation, it is desirable to have some means of adjusting the height of the table while the same is in place.

Third. It is also very desirable to be able to clean out the dirt or other refuse of the street, which works in around the edge of the table, without removing the top of the same.

Fourth. It is of great advantage to form the under side of its top in such a way that the water running into the table will not reach the wheels or balls on which the table revolves.

These objects and advantages are secured in the manner hereinafter described in detail, and particularly set forth in the claims.

In the accompanying drawings, Figure 1 shows in plan the top of the table, having a circumferential covered opening O and a central lift portion B. Fig. 2 is a vertical cross-section taken at the line x x of Fig. 1. Fig. 3 is a plan or top view of the turn-table with its top removed, showing a device for adjusting the height of the table. Fig. 4 is an enlarged plan or top view of the part E of Fig. 1, showing the stop devices for locking the turn-table; and Figs. 5 and 6 are cross-sec-

tions taken at the lines d d and e e, respectively, of Fig. 4. Fig. 7 is a cross-section taken at the line y y of Fig. 3.

In said figures the several parts are indicated by the letters of reference below used.

First. The locking-catch ordinarily used is constructed on the outside of turn-tables, forming an obstacle to the travel of vehicles over the same and subject, by reason of its exposed position, to be clogged and frozen up in cold weather. The locking-catch or stopping device, used in my invention corrects this defect, and is described as follows: In Fig. 4, which represents a partial plan on a larger scale, two bolts f f pass through holes h h in that part of the table shown at E, Fig. 1, and through eyes in the hinged latch G, which oscillates on the bolt g. When the table is to be turned, said bolts are drawn upward enough to permit their points to clear the slot H. The table is then revolved in the direction indicated by arrows until the bolts are clear of the slot, when they are dropped and allowed by the further revolution of the table to slide up the inclined guides of D, assisted by the latch G, which, being free to move radially on its bolt g, moves upward when the pressure against the incline forces the lower end of the bolts against it. The bolts then drop into the slot H, arresting the further turning of the table at the exact point of connection with the track-rail. It will be seen that the heads of these bolts rest even or flush with the surface of the table and do not offer any obstacle to the travel of horses or vehicles over the same; also, that all the rest of the stop or catch device, being under the top of the table and attached to the main frame in the interior, is protected thereby from the weather and from the débris of the street as well as from accidental damage.

To stop the revolving of the table at any given point, two or more bolts such as f may be placed on a line radially and at different distances from the center of the table, and stopping in slots H, similarly placed, may be so arranged that each bolt shall drop only in the slot set in the circular path in which it travels around the center. The heads of the bolts f, being T-shaped and working in slots in the table-top, may be all drawn up and held out of engagement, as shown in Fig. 5, except the par-

ticular bolt intended to stop the table at the point desired.

Second. The wheels or balls *b* are subject to wear, as well as the tracks on which they revolve. The main frame is also liable to settle. This constantly operates to lower the surface of the table, and to raise it to its proper level is in other forms of tables only accomplished by very cumbersome means of 5 awkward accessibility; but by my invention the upper rack *R* is detached from the frame of the table, and is provided with one or more inclined surfaces on the lower side, sliding on a similar inclined surface or surfaces cast 10 rigidly to the main frame, the two forming a double rack, the upper one of which, when rotated by any convenient means, raises or lowers the top of the table, as the case may be, securing the rack in its new position to 15 maintain said top at the desired elevation. Said rack can be rotated by wedges applied at different parts thereof, or by an adjusting screw or screws. One of the simplest ways of accomplishing this adjustment is shown in 20 Figs. 3 and 7, which is operated as follows: The ends of the bolt *P* are threaded to receive the nuts *N* and project through holes of convenient size in the lugs *M M*, which lugs are cast solid on a main frame or curb *C*. The 25 bolt *P* is also provided with collars *p p*, between which the lug *l* of the circular rack *R* is confined. To raise the rack *R*, and with it the top of the table *A*, it is only necessary to turn it in the proper direction by screwing 30 up against the lugs *M* with the nuts *N N*, the rotation of the movable rack *R* against the stationary rack *r*, Fig. 2, raising the table to the desired height. The rack *R* is held in place by the supports or lugs *L*, cast solid to the 35 bottom of the main frame on each side of the rack, which is allowed to move freely between them. It is obvious that the lower rack *r* might be made a movable rack and the upper rack *R* a stationary rack without departing from the principle of the device or accom- 40 45

plishing a different result. The entire center of the top is formed by a loose plate or cover *B*, which, when removed, gives room for removing refuse or dirt from under its central part without lifting the main body of 50 the table. The entire top may also be removed, if necessary, without disturbing the other parts of the table.

Third. The principal part of the refuse of the street accumulates between the lower rack 55 and the outside curb of the table. To facilitate the cleaning of this a small opening *O* provided with a cover is placed in the top near its circumference, so that by rotating the table access is given to the entire annular 60 space in which such refuse accumulates, and also in which to work the adjusting mechanism.

Fourth. The construction here shown prevents water from getting to the balls by providing a circular dripping-strip *S S*, Fig. 2, cast on the under side of the body of the top on the outer side of the balls, which strip prevents the water from running any farther in toward the center than the strip itself. A 70 similar dripping-strip *s s* is also cast on the inside to prevent water getting in and around the cover *B* from reaching the balls. In my invention hollow balls are preferably used, made in any convenient manner. Balls of 75 light weight and large diameter can thus be utilized, thereby lessening the expense and decreasing both the wear and the friction and making the tables revolve more easily.

Having thus fully described my said improvements, as of my invention I claim—

A turn-table provided with an adjustable circular rack, by whose adjustability or set 80 said table is raised or lowered, substantially as described, for the purposes set forth.

TOM L. JOHNSON.
